UNITED STATES PATENT OFFICE.

JOHN N. STURNER, OF BUFFALO, NEW YORK, ASSIGNOR OF ONE-HALF TO
ANTHONY J. THROM, OF BUFFALO, NEW YORK.

OIL-SEPARATOR.

No. 802,243.

Specification of Letters Patent.

Patented Oct. 17, 1905.

Application filed May 8, 1905. Serial No. 259,326.

To all whom it may concern:

Be it known that I, JOHN N. STURNER, a citizen of the United States, residing at Buffalo, in the county of Erie and State of New York, have invented a new and useful Improvement 5 in Oil-Separators, of which the following is a specification.

This invention relates to a separator for removing engine or other oil from water preparatory 10 to delivering the latter to a boiler. In devices for this purpose as heretofore constructed the oil was separated from the water and prevented from entering the boiler so long as the supply of water was sufficiently plentiful 15 to fill the pipes or conduits; but when the supply of water was so deficient that the conduits or pipes were not filled with water the level of the latter dropped to a point which permitted the oil floating on the same to be 20 drawn into the boiler, thus defeating the purpose of the separator, and consequently injuring the boiler.

The object of this invention is the production 25 of a device for separating oil from water which is more particularly designed to be placed in the water-feed line or pipe between an open water-heater and a pump feeding the boiler and which operates to separate the oil contained in the water and prevent the same 30 from passing into the boiler regardless of whether the water-supply is plentiful or deficient.

In the accompanying drawings, Figure 1 is 35 a vertical section of my improved oil-separator. Fig. 2 is a horizontal section of the same in line 2 2, Fig. 1.

Similar letters of reference indicate corresponding parts throughout both views.

A represents the separating-chamber, which 40 is preferably of vertically-elongated form. This chamber is constructed in sections *a a'*, which are connected by bolts *a²*, the joint between the sections being about midway of the height of the chamber. The lower part or 45 section of the chamber is provided with an inlet-nipple B and an outlet-nipple C, which are horizontally in line and preferably on opposite sides of the chamber. The inlet-nipple is connected by a pipe or conduit *b* with 50 the water supplied from a heater or other source. The outlet-nipple is connected by a pipe or conduit *c* with the boiler or with the pump whereby the water is delivered to the boiler to be fed. Within the separating-

chamber is arranged a drop pipe or nozzle D, 55 which extends from the outlet-nipple downwardly toward the bottom of the chamber and opens at its lower end into the chamber at a distance below the inlet and outlet nipples.

In the ordinary operation of the separator 60 the oil-bearing water enters the chamber through the inlet-nipple and fills the same. Within the chamber the oil separates from the water and rises to the top of the water at the upper end of the chamber and is drawn 65 off from time to time by a blow-off pipe F, connecting with the top of the chamber and containing a valve *f*. The purified water descends to the lower end of the chamber and is drawn off through the drop-pipe, outlet-nipple, and delivery-pipe. Any sediment collecting 70 in the bottom of the separating-chamber is removed when necessary by a blow-off pipe G, connecting with the bottom of the chamber and containing a valve *g*. 75

The water-supply sometimes becomes temporarily deficient, and if no means were provided to prevent it the water and oil at this time would be entirely exhausted from the chamber and fed to the boiler, thus effecting 80 the latter injuriously. In order to prevent oil from being drawn in this manner into the boiler when a deficient water-supply occurs, means are provided for interrupting or breaking the suction or effect of the pump before 85 the level of the water in the separating-chamber drops below the inlet and outlet nipples thereof. The preferred means for this purpose shown in the drawings are constructed as follows: H represents a trap or safety pipe 90 or conduit arranged in the upper part of the separating-chamber and consisting of a long vertical branch or section *h*, which is connected at its lower end with the outlet-nipple of the chamber, and a short vertical branch or section *h'*, which is connected at its upper end with the upper end of the long section, while its lower end is open and terminates at a distance above the inlet and outlet nipples of the separating-chamber. The safety-pipe thus 95 has substantially the form of an inverted U, one leg or branch of which is longer than the other. As the water fills the inlet and outlet conduits and rises in the separating-chamber it also rises in both branches or sections of 100 the trap and compresses the air confined in the connected upper ends of the same, thereby forming an air-plug, check, or partition which 105

prevents the water from being drawn from the chamber through the short branch of the trap over into the long branch thereof and out through the outlet thereof. The exit of the water from the chamber is thus confined to the drop-pipe, whereby only purified water is withdrawn from the lower part of the chamber, leaving the oil floating on top of the water undisturbed, thereby preventing the oil from reaching the boiler. If the supply of water for any reason becomes deficient, the level of the water in the chamber gradually lowers by the withdrawal of the water from the lower part of the chamber. As the water-level descends in the chamber it also lowers in the branches of the trap. While the water thus lowers the lower end of the short branch of the trap is uncovered, thereby placing this branch, which is now empty, in communication with the empty upper part of the separating-chamber. When the level of the water in continuing its descent drops below the top of the inlet and outlet nipples of the chamber, air or steam is carried from the inlet-nipple successively through the upper part of the separating-chamber, trap-pipe, and outlet-nipple to the boiler or to the pump which feeds the water to the boiler. When this occurs, the pump loses its priming on account of becoming either air or steam bound and immediately ceases to withdraw water from the chamber and deliver the same to the boiler. This stopping of the feeding operation of the pump occurs the instant the liquid-level in the chamber drops below the top of the inlet and outlet nipples and before this liquid-level reaches the lower end of the drop-pipe. The oil which is floating on top of the water is thus retained in the separating-chamber and prevented from being forced or drawn by the pump from the chamber with the last of the water in the same and delivered to the boiler, whereby injury to the latter which otherwise would result is positively avoided. When the normal supply of water is again restored, the same rises in the separating-chamber and lifts the oil to the top thereof, when the same can be blown off when required, and the lower ends of the branches of the trap are again sealed by the water, so as to form a partition or body of air in the upper end of the same, thus placing the apparatus in condition for resuming the feed of water to the boiler and the separation of the oil therefrom.

For the purpose of enabling the attendant to determine the level of the water and oil in the chamber the latter is provided with a visual indicator consisting, preferably, of two sections I I' of a glass gage, which connect

with the upper and lower parts of the chamber, as shown in the drawings.

I claim as my invention—

1. A device for separating oil from water comprising a closed separating-chamber having a liquid-inlet and a liquid-outlet, a drop-pipe extending from said outlet into the chamber below said inlet, and a safety-pipe having its opposite ends opening into said outlet and into the chamber above the lower end of said drop-pipe, substantially as set forth. 60

2. A device for separating oil from water comprising a chamber having an inlet and an outlet, a drop-pipe extending from said outlet downwardly into the lower part of said chamber below said inlet, and a safety pipe 75 or conduit having its opposite ends opening into said outlet and the upper part of said chamber, substantially as set forth.

3. A device for separating oil from water comprising a chamber having a liquid-inlet 80 and a liquid-outlet horizontally in line, a drop-pipe extending from said outlet downwardly into the lower part of said chamber below said inlet, and a safety-pipe having the form of an inverted **U** one branch of which opens at its 85 lower end into said outlet while its other branch opens into the upper part of said chamber, substantially as set forth.

4. A device for separating oil from water comprising a chamber having a liquid-inlet 90 and a liquid-outlet horizontally in line, a drop-pipe extending from said outlet downwardly into the lower part of said chamber below said inlet, and a safety-pipe having the form of an inverted **U** one branch of which is long and 95 opens into said outlet while the other branch is short and opens into the upper part of said chamber, substantially as set forth.

5. A device for separating oil from water comprising a chamber having a liquid-inlet 100 and a liquid-outlet on horizontally opposite sides, a sediment blow-off at its bottom and an oil blow-off at its top, a drop-pipe extending from said outlet downwardly in said chamber below said inlet and outlet, and a safety-pipe 105 of inverted-**U** form arranged in the upper part of said chamber and having a long branch which connects at its lower end with said outlet and a short branch which opens at its lower end into the chamber above said inlet, substantially as set forth. 110

Witness my hand this 29th day of April, 1905:

JOHN N. STURNER.
